(57) **CLAIM**

The ornamental design for a lamp, as shown and described.

DESCRIPTION

FIG. 1 is a front-right-top perspective view of a lamp in a first orientation, showing the new design;

FIG. 2 is a rear-left-bottom perspective view thereof;
FIG. 3 is a front elevation view thereof;
FIG. 4 is a rear elevation view thereof;
FIG. 5 is a right elevation view thereof; the left side elevation view being a mirror image of FIG. 5;
FIG. 6 is a top plan view thereof;
FIG. 7 is a bottom plan view thereof;
FIG. 8 is a front-right-top perspective view of the lamp in a second orientation;
FIG. 9 is a rear-left-bottom perspective view thereof;
FIG. 10 is a right side elevation view thereof; the left side elevation view being a mirror image of FIG. 10;
FIG. 11 is an enlarged view of portion 11 shown in FIG. 9;
FIG. 12 is a front-right-top perspective view of the lamp in a third orientation;
FIG. 13 is a rear-left-bottom perspective view thereof;
FIG. 14 is a right side elevation view thereof; the left side elevation view being a mirror image of FIG. 14;
FIG. 15 is an enlarged view of portion 15 shown in FIG. 13;
FIG. 16 is a front-right-top perspective view of the lamp in a fourth orientation;
FIG. 17 is a rear-left-bottom perspective view thereof;
FIG. 18 is a right side elevation view thereof; the left side elevation view being a mirror image of FIG. 18;
FIG. 19 is an enlarged view of portion 19 shown in FIG. 17;
FIG. 20 is a front-right-top perspective view of the lamp in a fifth orientation;
FIG. 21 is a rear-left-bottom perspective view thereof;
FIG. 22 is a right side elevation view thereof; the left side elevation view being a mirror image of FIG. 22; and,
FIG. 23 is an enlarged view of portion 23 shown in FIG. 21. The dash-dash broken lines depict portions of the lamp that form no part of the claimed design.
The dash-dot lines in FIGS. 9, 11, 13, 15, 17, 19, 21, and 23 illustrate the boundaries of the enlarged view indicators and form no part of the claimed design.

1 Claim, 23 Drawing Sheets
